UNITED STATES PATENT OFFICE.

PETER J. STEIGER, OF NEWARK, NEW JERSEY.

STAY-HINGE.

1,042,985.

Specification of Letters Patent.

Patented Oct. 29, 1912.

Application filed January 21, 1911. Serial No. 603,882.

To all whom it may concern:

Be it known that I, PETER J. STEIGER, citizen of the United States, residing at Newark, in the county of Essex and State 5 of New Jersey, have invented certain new and useful Improvements in Stay-Hinges; and I do hereby declare the following to be a full, clear, and exact description of the invention, such as will enable others skilled in 10 the art to which it appertains to make and use the same, reference being had to the accompanying drawings, and to characters of reference marked thereon, which form a part of this specification.

15 This invention relates, generally, to improvements in hinges; and the invention has reference, more particularly, to that class of hinges known in the art as stay-hinges, and which are more especially adapted for use 20 with trunks and dress-boxes.

The present invention has for its principal object to provide a novel and simple construction of hinge with suitable means connected with the hinged leaves or sections of the hinge 25 and acting automatically and coöperating with the said hinge-sections to limit or arrest their pivotal movement when the lid or cover of the trunk or box is opened, and thereby to safely retain the said lid or cover 30 in its opened position without any danger of the usually heavy lid or cover breaking the hinge-connection, or otherwise destroying the usefulness of the hinge.

Other objects of this invention not at this 35 time more particularly enumerated will be clearly obvious from the following detailed description of the same.

With the various objects of the present invention in view, the said invention consists 40 primarily, in the novel lock or stay-hinge hereinafter set forth; and, the invention consists, furthermore, in the novel arrangements and combinations of the various parts, as well as in the details of the construction 45 of the same, all of which will be more fully described in the following specification, and then finally embodied in the clauses of the claim which is appended to and which form an essential part of this specification.

50 The invention is clearly illustrated in the accompanying drawings, in which:—

Figure 1 is a face view of a hinge showing one embodiment of the principles of the present invention, the same being represented 55 in its affixed position to a body and a lid of a trunk, dress-case, or the like, said

body and lid being represented in part only; Fig. 2 is a transverse sectional representation of the various parts illustrated in said Fig. 1, said section being taken centrally 60 through the hinge; and Fig. 3 is a sectional representation of the trunk or case-body and lid, with the lock or stay-hinge in side elevation, and the parts thereof being represented in their open and "stayed" relation. 65 Fig. 4 is a view similar to that represented in Fig. 1 of portions of the trunk or case-body and lid, with a face view of a lock or stay-hinge therefor, said hinge, however, being slightly modified in construction; and Fig. 5 is a transverse vertical sectional representation of the parts illustrated in said Fig. 4, said section being taken centrally 70 through the hinge.

Similar characters of reference are employed in all of the above described views, 75 to indicate corresponding parts.

Referring now to the several figures of the drawings, the reference-character 1 indicates the body of a trunk or dress-case and 80 2 the lid or cover of the same which is preferably provided with the usual valance 3. The hinge proper, in this instance as here shown, is of the usual hinge construction such as is employed with trunks; and, the 85 same consists of the usual hinge-leaves or sections 4 and 5 suitably pivotally connected by means of the knuckles 6 and 7 and a pin or pintle 8, the said hinge-leaves or sections 4 and 5 being secured to the body 1 and the 90 lid 2 by means of the usual rivets 9, or similar fastening devices. Suitably secured upon the face of the hinge-leaf or section 4, by means of some of the said rivets 9, is a plate 10, said plate being provided with a suitably 95 struck-out eye, as 11, forming a bearing-portion, in which are pivotally arranged the end-portions 13 and 14 of a frame-like stay 12 which is preferably made from spring-wire of suitable gage and strength, and is 100 preferably of the configuration shown in the several figures of the drawings. This stay 12, as shown, is made with the upper and outwardly extending members 15 and 16 connected with the respective end-portions 13 and 14, and connected with the 105 respective members 15 and 16 are the lower and inwardly extending members 17 and 18, said members 17 and 18 being connected by means of a cross-bar 19. The construction 110 of the frame-like stay 12 is such that its end-portions 13 and 14 can be sufficiently sepa-

rated so as to be readily sprung into its hinged or pivotal connection with the bearing-portion 11, as will be clearly evident. It will also be understood, that while the 5 configuration of the frame-like stay 12 shown in the drawings is the preferred form, the general shape and configuration of the said frame-like stay may be changed, if desired. Suitably secured upon the face of 10 the hinge-leaf or section 5, by means of some of the said rivets 9, is a plate 20, said plate being formed with an offset part, as 21, which provides a suitable guide in the space 22 in which the bar-like portion 19 of 15 the frame-like stay 12 is slidably arranged, as shown.

The operations of the several parts hereinabove described will be clearly understood from an inspection of Figs. 1, 2 and 3 of the 20 drawings, the downward sliding movement of the frame-like stay 12 being limited by the cross-bar 19 of the stay being brought into engagement with the part 23 of the plate 20 which acts as a stop, so as to bring 25 the parts into the fixed positions shown in Fig. 3 of the drawings, and thereby positively and rigidly retaining the lid or cover 2 in its open position with relation to the body or box 1, and at the same time removing 30 all undue strain from the hinge-connection of the hinge, and preventing the lid or cover from dropping suddenly and too far down, thus preventing the breaking of the hinge, or otherwise rendering the same 35 inoperative.

Instead of providing the hinge-section 4 with a plate 10 independently secured to said hinge-section by means of the rivets 9, or otherwise, the said hinge-section may 40 have struck up or forced out of its body-portion a tongue 24, as shown in Figs. 4 and 5 of the drawings, said tongue being provided with a suitably bent part, as 25, forming a bearing-portion for the same purpose 45 as the bearing-portion 11 used in connection with the plate 10.

In like manner, the lower hinge-section 5 is formed with an upwardly extending tongue 26 which is forced out of or struck 50 from the body-portion of said hinge-section, the said tongue 26 being formed with the bent parts 27 and 28, which provide with the body of said tongue a suitable guide for the slidable arrangement 55 therein of the bar-like portion 19 of the

frame-like stay 12, the lower bent part 27 acting as a stop in the manner of and for the same purposes as the bent part 23 of the plate 20 hereinbefore described in connection with the construction shown in Figs. 60 1, 2 and 3 of the drawings.

The manner of connecting the frame-like stay 12 with the tongues 24 and 26 of the respective hinge-leaves or sections of the hinge represented in said Figs. 4 and 5 is 65 the same as that described with the construction represented in said Figs. 1, 2 and 3. The operations of the parts are also the same, and being self-evident from an inspection of said Figs. 4 and 5, need not be further described.

I am fully aware that some changes may be made in the general arrangements and combinations of the various parts, as well as in the details of the construction of the 75 same, without departing from the scope of this invention as set forth in the foregoing specification, and as defined in the claims which are appended thereto. Hence, I do not limit my invention to the exact arrangements and combinations of the parts as described in said specification, nor do I confine myself to the exact details of the construction of the said parts as illustrated in the accompanying drawings. 80

I claim:

A stay-hinge for trunks, boxes and the like, comprising a pair of hinged sections, a tongue struck up out of one of said hinge-sections, a bearing-portion connected with 90 said tongue, a frame-like stay pivotally mounted at one end in said bearing-portion, a tongue struck up out of the other hinge-section, said last-mentioned tongue having bent parts so as to form a guide, said frame-like stay having a bar-like member slidably disposed in said guide, and one of said bent portions of said last-mentioned tongue forming a stop with which said bar-like member is adapted to be brought in engagement for limiting the sliding movement of 95 said frame-like stay and retaining said hinge-sections in their open relation.

In testimony that I claim the invention set forth above I have hereunto set my hand 105 this 17th day of January, 1911.

PETER J. STEIGER.
